MATCH BOOK COVER

Reni S. Berry, Los Angeles, Calif., assignor to
Sydney J. Levy, Los Angeles, Calif.

Application October 26, 1938, Serial No. 237,153

7 Claims. (Cl. 206—29)

This invention relates to book matches of the character embodying a battery of matches mounted in a cover embodying a cover flap and a holding tongue and fitted with a striking surface; the present invention more particularly pertaining to the match book cover and the mode of equipping same with a striking surface.

An object of the invention is to provide a construction and arrangement in match book covers of the above character whereby striking of the match on the striking surface while the cover flap is open will be rendered quite difficult and such that the striking action will be greatly facilitated when the cover flap is closed so as to encourage the practice of closing the cover flap before striking the match and thus minimize accidental ignition of the matches contained in the book by flame propagated from the struck match.

Another object is to provide a striking surface on a match book which is so formed as to present an angular formation to one side and the end of a match head struck thereon so as to afford a guide for a match and thereby facilitate striking of the match by the sense of feel and whereby ignition action on the match is augmented.

A further object is to provide a match book in which the striking surface is so arranged as to serve when the match book cover is in its closed position to yieldably resist disengagement of the cover flap from the holding tongue.

A further object is to provide an improved arrangement of the striking surface on match books which while affording the advantageous features above set forth will require no alteration in the mode of construction and assembly of the match book other than as to the manner of applying the composition used in forming the match striking surface.

With the foregoing objects in view, together with such other objects and advantages as may subsequently appear, the invention is carried into effect as illustrated by way of example in the accompanying drawing, in which:

Fig. 1 is a perspective view of the match book showing the cover thereof in a partly open position;

Fig. 2 is a perspective view of the match book showing the cover in its closed position and depicting the manner in which a match is applied to the striking surface;

Fig. 3 is an enlarged detail in section taken on the line 3—3 of Fig. 2;

Fig. 4 is a perspective view of a slightly modified form of the invention; and

Fig. 5 is an enlarged detail in section taken on the line 5—5 of Fig. 4.

Referring to the drawing more specifically A indicates generally the match book cover which embodies a back portion 6 one end of which terminates in a return bend 7 between which and the back portion 6 is affixed a battery of matches B as by means of a staple 8, and the other end of which terminates in a cover flap 9 through a bendable section 10; the outer end of the cover flap being insertable under a holding tongue 11 formed in continuation of the return bend 7. This cover A with its match assembly constitutes a conventional type of match book construction in which the cover is formed of a length of flexible paper and the matches are formed of a paper ribbon 12 which is slit to form a row of match stems 13 along one margin thereof and of which stems are fitted with match heads 14 at their outer ends; the matches being enclosed in the cover A when the cover flap 9 thereof is engaged under the holding tongue 11 and being exposed on swinging the cover flap outwardly away from the holding tongue, and the matches being adapted to be separated from the ribbon 12 by rending the stems 13 thereof from the ribbon.

The present invention primarily resides in forming a striking surface C along the margin of the holding tongue 11 in such manner that in order to facilitate striking a match thereon the cover flap 9 is to be disposed in its closed position. As here shown this is accomplished by forming a bead 15 of match striking composition along the end edge of the tongue and also forming a narrow strip 16 of like composition transversely of the outer face of the cover flap 9 proximate to but spaced from the end margin of the flap and in such position that when the end of the flap is disposed in engagement with the holding tongue 11 the strip 16 may be exposed at least in part along the length thereof contiguous the bead 15 so as to form with the latter a striking surface extending transversely of the cover which substantially conforms laterally thereof to a right angle; the bead 15 forming an upstanding shoulder along one marginal portion of the strip 16 such as to serve as a guide for directing the head of a match along the strip 16. While the bead 15 and strip 16 may be formed of substantial widths it is desirable to the end of necessitating closing of the cover leaf in order

to afford ample striking surface, that the bead 15 and strip 16 each be of such narrowness as to render striking of a match thereon separately quite difficult if not impossible, but when the bead and strip are combined with the bead 15 extending along the strip 16 with the latter exposed the requisite striking surface will be provided.

- The strip 16 may be located on the flap 9 such that when the flap is in its closed position a portion of the strip 16 will be exposed along the bead 15 as shown in Fig. 3, but manifestly the strip 16 may be so located on the flap 9 that when the latter is in its fully closed position the strip 16 will be concealed and covered by the holding tongue 11 as shown in Figs. 4 and 5, in which latter arrangement the cover flap is to be partly withdrawn from engagement with the holding tongue to expose the strip 16 as indicated by the dotted lines *a* in Fig. 5. By thus concealing the striking strip 16 when the cover flap is closed the strip is protected when not in use from deterioration as by contact with moist hands and abrasive surfaces. However, the upstanding shoulder formed by the bead 15 will serve to some extent in protecting the surface of the exposed strip 16 from coming in contact with damaging surfaces. This protective feature enhances the durability of the striking compound.
- Another advantageous feature derived from the employment of the pair of cooperating striking elements 15 and 16 is that when the cover flap is closed a frictional engagement between the bead 15 and strip 16 will be effected which by reason of the roughness of the contiguous surfaces of the striking material will serve to resist withdrawal of the cover flap from engagement with the holding tongue, thus in effect releasably fastening the cover flap in its closed position.
- In equipping the tongue with the bead 15 the margin of the paper strip of which the tongue is formed is preferably dipped in a body of the striking composition as by running the edge of the paper strip through a fluid batch of the composition during the course of manufacture of the book by the usual match book making machinery. However the bead 15 may be applied to the edge of the tongue by applicator rollers as by passing the edge of the paper strip over the periphery of a grooved roller having a portion of its perimeter submerged in a batch of the compound. In thus forming the bead the material thereof will overlie the edge of the tongue and will extend slightly along the marginal surface of each side thereof as shown in Figs. 3 and 5.
- The operation of the invention is apparent from the foregoing, it being seen that when the cover flap 9 is in its closed position with its outer end underlying the holding tongue 11, the striking surface 16 may be positioned to protrude forward of the bead 15 as shown in Figs. 2 and 3 and as indicated in dotted lines *a* in Fig. 5, and thus provide adequate striking surface for a match D the head 14 of which is positioned with its tip on the surface 16 and with one side thereof abutting the bead 15 as indicated in dotted lines in Fig. 3, whereupon the match head is drawn lengthwise of the striking strip, that is transversely of the cover, as illustrated in Fig. 2, such as to effect ignition of the match. The double contact of the bead 15 and strip 16 on the side and tip of the match head insures quick igniting action, while the shoulder afforded by the bead 15 acts to guide the match along the striking surface and thus facilitate lighting of the match

by the sense of feel as in striking the match in the dark.

The important feature of the invention resides in the fact that when the cover flap is open, the bead 15 will present insufficient scratching surface to effect easy ignition of the match, and the same is true as to the strip 16 with the added condition of the strip being located on the free end of the cover flap such that by reason of flexibility of the latter renders it quite difficult to scratch a match.

While I have shown and described a specific embodiment of my invention I do not limit myself to the exact details of construction set forth, and the invention embraces such changes, modifications and equivalents of the parts and their formation and arrangement as come within the purview of the appended claims.

I claim:

1. In a match book cover having a cover flap and a holding tongue arranged for overlapped engagement of the outer end of said cover flap, a bead of striking composition on the margin of said tongue presented toward said cover flap, and a strip of striking composition on the outer face of said cover flap arranged to extend contiguous said bead in an exposed position when the end of said cover flap is engaged by said tongue, said bead and strip constituting collectively a striking surface and said bead forming a guide shoulder intermediate the edges of such surface.

2. In a match book cover having a cover flap and a holding tongue, a striking bead on the end edge of said tongue, and a striking strip on said cover flap; said bead and strip forming collectively a striking surface of substantially angular cross section leading transversely of the cover when the outer end of the cover flap is positioned beneath said holding tongue.

3. In a match book cover having a cover flap and a holding tongue arranged to overlap the outer end of said cover flap when the latter is in a closed position, a narrow strip of striking surface extending transversely of said cover flap adjacent the outer end thereof arranged to be exposed along the end edge of said tongue when said cover flap is in a partly closed position, and a strip of striking material on the end edge of said tongue cooperating with said strip of striking surface on said flap to afford a striking surface of greater width than is afforded by said strip or bead alone.

4. In a match book cover having a cover flap and a holding tongue arranged to overlap the outer end of said cover flap when the latter is in a closed position, a narrow strip of striking surface extending transversely of said cover flap adjacent the outer end thereof arranged to be exposed along the end edge of said tongue when said cover flap is in a partly closed position, and a bead on the end edge of said tongue forming a guide shoulder lengthwise of said striking strip adjacent an edge thereof when said cover flap is in a closed or nearly closed position.

5. In a match book cover having a cover flap and a holding tongue arranged for overlapped engagement of the outer end of said cover flap, a bead of striking composition on the margin of said tongue presented toward said cover flap forming a combined guide shoulder and striking surface along the end face of said tongue, and a striking strip on said cover flap arranged to underlie said tongue in engagement with said bead when the outer end of said cover flap is over-

lapped by said tongue to resist disengagement of the cover flap from said tongue.

6. In a match book cover having a cover flap and a holding tongue arranged to overlap the outer end of said cover flap when the latter is in a closed position, a striking bead on the end edge of said tongue protruding on the underside thereof, a narrow strip of striking surface extending transversely of said cover flap adjacent the outer end thereof arranged to be exposed along the end edge of said tongue when said cover flap is in a partly closed position; said holding tongue having its end edge arranged to form with said striking bead a guide shoulder projecting outwardly from said striking surface when the outer end of said cover flap is overlapped by said holding tongue with said striking surface exposed contiguous the end edge of said tongue, and said strip of striking surface being engageable with the protruding portion of said bead to resist

withdrawal of the end portion of said cover flap from beneath said tongue.

7. In a match book cover having a cover flap and a holding tongue arranged to overlap the outer end of said cover flap when the latter is in a closed position; a narrow strip of striking surface extending transversely of said cover flap adjacent the outer end thereof arranged to be exposed along the end edge of said tongue when said cover flap is in a partly closed position and to be concealed beneath said tongue on advancing the cover flap to a fully closed position, and a striking bead on the end margin of said tongue protruding outwardly relative to said striking surface to form therewith a match guide when the cover flap is in a partly closed position and being arranged to engage a side margin of said strip of striking surface when said cover flap is in its fully closed position to resist withdrawal of said cover flap from beneath said tongue.
